(57) **CLAIM**

The ornamental design for a television receiver, as shown and described.

DESCRIPTION

1. Television receiver

1.1 : Perspective

1.2 : Front

1.3 : Back

1.4 : Left

1.5 : Top

1.6 : Perspective view 2

1.7 : Front view 2

1.8 : Back view 2

1.9 : Left view 2

1.10 : Top view 2

The fine oblique lines on the drawings indicate the display portion of the television receiver; reproduction 1.1 is a perspective view of the television receiver in a folded state; reproductions 1.2 to 1.5 are front, back, left and top views of reproduction 1.1 where the right and bottom views are mirror images of the left and top views; reproduction 1.6 is a perspective view of the claimed design in an unfolded state; reproductions 1.7 to 1.10 are front, back, left and top views of reproduction 1.6 where the right and bottom views are mirror images of the left and top views.

1 Claim, 10 Drawing Sheets
